UNITED STATES PATENT OFFICE.

LOUIS P. WHITEMAN, OF NEW YORK, N. Y.

JAR FOR MILK, &c.

SPECIFICATION forming part of Letters Patent No. 225,900, dated March 23, 1880.

Application filed January 31, 1880.

To all whom it may concern:

Be it known that I, LOUIS P. WHITEMAN, of the city, county, and State of New York, have invented a certain new and useful Improvement in Jars for Milk and other Articles, 5 of which the following is a specification.

The object of my invention is to provide for using, in conjunction with a glass jar furnished with a cover of the same material, a desirable 10 fastening for retaining the cover in place.

To this end my invention consists in the combination, with a glass jar and a glass cover therefor, provided on the exterior with a boss having a groove extending transversely across 15 the top and a circumferential groove or projection just below the top, of a bail-like wire for fastening the cover in place, fitting in the said transverse groove, and a cap-piece of metal or other suitable material fitting over the top of 20 the said boss, and having its edges creased over or otherwise made to engage with the circumferential groove or projection, whereby the bail-like wire is effectually secured to the glass cover and the desired end is attained.

25 In the accompanying drawings, Figure 1 is a central vertical section of the upper part of a glass-jar cover and fastener embodying my invention. Fig. 2 is a perspective view of the cap-piece above named detached, and Fig. 3 30 is a side view of a cover and transverse section of a cap-piece and bail embodying my invention in a slightly-modified form.

Similar letters of reference designate corresponding parts in all the figures.

35 A designates the upper part of a jar of glass, which may be of any suitable shape, and B designates a glass cover fitting in the mouth of the jar, and furnished with a flange overlapping the mouth of the jar, and sealing it 40 with the aid of a packing-ring, p, preferably of cork.

On the exterior of the cover is a boss, a, 45 formed of glass in the same piece with the cover. Across the top of this boss is a transverse groove, b, in which fits a bail-like wire, C. In a boss, a, is a circumferential groove, c, near the top thereof.

D designates a cap-piece, of sheet metal, which is fitted over the top of the boss a, and

has its edges tamped, creased, or otherwise 50 bent and turned into the circumferential groove c. The edges of this cap-piece bear on the bail-like wire C and retain it in the transverse groove b, securing the cover B to the bail-like wire, so that it may turn or swivel on the said 55 wire.

In Fig. 3 I have shown a glass cover, B, like the one above described, but having a boss, a', provided with a transverse groove, b, but having a projection or screw-thread, d, formed 60 circumferentially on its exterior.

D' designates a cap-piece of sheet metal or other suitable material, provided internally with a screw-thread, whereby it is secured to the boss a'. Its edges bear against the bail-like wire C and hold it in the groove, as in the above-described example of my invention. 65

The ends of the bail-like wire C have a pivotal connection with a lever, G, consisting of a bow-shaped wire fitting the neck of the jar A, 70 when the cover is in place, having loops l, formed by twisting it, for the reception of the bail-like wire C, and having arms m, bent up from these loops nearly at right angles to its main portion and fastened to a neck-wire, H. 75 The fastening thus produced is of a form common in bottles, and provides for releasing the cover B easily by pushing against the arms m, so as to force the bow portion of the lever G away from the neck of the jar, and it provides 80 for readily fastening the cover, when in place, by forcing the bow portion of the lever G into contact with the neck of the jar.

By my invention I provide for packing milk in a jar having a cover of glass and a secure 85 and convenient fastening for the cover, which has the cover attached to it. As the contents of the jar come in contact only with glass, its quality will not become impaired thereby. As glass is a non-conductor of electricity, milk 90 contained in the jar will be kept sweet during thunder-storms.

The jars and covers can be easily and thoroughly cleansed, and owing to the attachment of the cover to its fastening it is not liable to 95 be lost or mislaid.

What I claim as my invention, and desire to secure by Letters Patent, is—

The combination, with a glass jar and a glass cover therefor, provided on the exterior with a boss having a groove extending transversely across, and a circumferential groove or projection just below the top, of a bail-like wire for fastening the cover in place, fitting in said transverse groove, and a cap-piece of metal or other suitable material having its edges

creased over or otherwise made to engage with the circumferential groove or projection, substantially as and for the purpose specified.

LOUIS P. WHITEMAN.
